US0D1100146S

(12) **United States Design Patent** (10) **Patent No.:** **US D1,100,146 S**
(45) **Date of Patent:** ** *Oct. 28, 2025

(54) **SPACER**

(71) Applicant: **Graco Minnesota Inc.**, Minneapolis, MN (US)

(72) Inventors: **James R. Ebbin**, Shoreview, MN (US); **Anthony J. Kuschel**, Coon Rapids, MN (US); **Daniel M. Jensen**, Mahtomedi, MN (US); **Bradley G. Kahler**, Otsego, MN (US)

(73) Assignee: **Graco Minnesota Inc.**, Minneapolis, MN (US)

(*) Notice: This patent is subject to a terminal disclaimer.

(**) Term: **15 Years**

(21) Appl. No.: **29/987,947**

(22) Filed: **Jan. 28, 2025**

E03C 2001/028; E03C 1/264; E04D 13/0409; F16K 11/00

CLAIM

The ornamental design for a spacer as shown and described.

DESCRIPTION

FIG. 1 is a first isometric view of a spacer;
FIG. 2 is a second isometric view of the spacer;
FIG. 3 is a front elevational view of the spacer;
FIG. 4 is a left side view of the spacer;
FIG. 5 is a right side view of the spacer;
FIG. 6 is rear elevational view of the spacer;
FIG. 7 is a bottom plan view of the spacer; and,
FIG. 8 is a top plan view of the spacer.
The broken lines shown in the Figures represent portions of
a spacer that form no part of the claimed design.

1 Claim, 2 Drawing Sheets
